AUTOMOBILE AVERAGE SPEED INDICATOR

William E. Rintelmann, Naugatuck, Conn.

Application September 18, 1956, Serial No. 42,983

Term of patent 3½ years

(Cl. D52—1)

Fig. 1

Fig. 2

Fig. 1 is a front view in elevation of the automobile average speed indicator, showing my new design.

Fig. 2 is a side view of the same.

I claim:

The ornamental design for the automobile average speed indicator, substantially as shown.
